DECORATIVE VEGETATION SUPPRESSING SUR-
ROUND FOR GRAVE MARKING STRUCTURES

Joseph J. Matvey, 1100 Penn Center Blvd.—615
Pittsburgh, Pa. 15235

Filed Feb. 11, 1972, Ser. No. 225,705

Term of patent 14 years

Int. Cl. D31

U.S. Cl. D79—2

FIG. 1.

FIG. 2.

FIG. 3.

FIG. 4.

FIG. 5.

FIG. 6.

FIG. 1 is a top plan view of the decorative vegetation suppressing surround for grave marking structures of this invention.

FIG. 2 is a bottom plan view of the decorative vegetation suppressing surround for grave marking structures of this invention.

FIG. 3 is a cross sectional illustration of the surround taken through 3—3 of FIG. 1.

FIGS. 4 through 6 are cross sectional views, similar to FIG. 3, but each showing different embodiments of the design with modified profiles.

I claim:

The ornamental design for a decorative vegetation suppressing surround for grave marking structures, substantially as shown and described.
